Primary Examiner — Susan Bennett Hattan*Assistant Examiner* — Marie Fast Horse(74) Attorney, Agent, or Firm — Novick, Kim & Lee, PLLC; Sang Ho Lee(57) CLAIM

The ornamental design for a holder for smart phone or the like, as shown and described.

DESCRIPTION

FIG. 1 is a perspective view of a holder for smart phone or the like;

FIG. 2 is a left elevational side view thereof;

FIG. 3 is a right elevational side view thereof;

FIG. 4 is a front view thereof;

FIG. 5 is a rear view thereof;

FIG. 6 is a top plan view thereof;

FIG. 7 is a bottom plan view thereof;

FIG. 8 is a perspective view thereof, in an alternate position for use; and,

FIG. 9 is a perspective view thereof, holding a smart phone. The broken lines in FIG. 9, showing the smart phone, depict unclaimed environment and form no part of the claimed design.
